UNITED STATES PATENT OFFICE.

JOHN J. BRADNER, OF FINDLAY, OHIO.

GROCER'S SCOOP.

SPECIFICATION forming part of Letters Patent No. 255,923, dated April 4, 1882.

Application filed February 28, 1882. (No model.)

To all whom it may concern:

Be it known that I, JOHN J. BRADNER, of Findlay, in the county of Hancock and State of Ohio, have invented a new and useful Improvement in Grocers' Scoops, of which the following is a clear, full, and exact description, reference being had to the accompanying drawings, making a part of this specification, in which—

10 Figure 1 is a perspective view of a scoop with my improvements attached. Fig. 2 is a plan view of the same.

The object of my invention is to furnish a scoop devoid of any metallic surface and so constructed as to possess sufficient strength to stand any legitimate use, while it is light and easily handled; and it consists in making the scoop entirely of wood and securing the blade to the scoop-head in the manner described and

20 claimed.

To enable others skilled in the art to make and use my invention, I will proceed to describe the exact manner in which I have carried it out.

25 Scoops as now used have a metallic surface, which is liable to be affected by many articles and become corroded and dangerous to health; and to overcome this difficulty is one object of my invention.

In the drawings, A represents a scoop-blade 30 formed of wood, with a regular curve, and at its rear edge is provided with a tenon, a, against which the outer edge of the scoop-head rests. The scoop-head B is recessed at b, as shown in Fig. 2, and into this recess fits the rear edge, 35 e, of the blade. The blade and scoop-head then are glued or otherwise securely fastened together, forming a strong, light scoop, which is easily kept clean and not liable to be injuriously affected by grocers' goods. It is evident from this construction of the two parts that I not only secure a large bearing-surface between the parts, but that each part tends to 40 secure and hold the other firmly in position.

Having thus described my invention, what 45 I claim, and desire to secure by Letters Patent, is—

In a wooden scoop, the blade A, provided with the tenon a and rear edge, e, in combination with the head B, provided with the recess 50 b, constructed and arranged substantially as and for the purpose set forth.

JOHN J. BRADNER.
